UNITED STATES PATENT OFFICE.

ARNOLD STEIGER AND WILHELM STEIGER, OF ZURICH, SWITZERLAND.

SHAFT-KILN.

1,287,505.

Specification of Letters Patent. Patented Dec. 10, 1918.

Application filed August 4, 1917. Serial No. 184,543.

To all whom it may concern:

Be it known that we, ARNOLD STEIGER and WILHELM STEIGER, both being citizens of the Republic of Switzerland, and residents of Zurich, Switzerland, have invented certain new and useful Improvements in Shaft-Kilns; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention has reference to improvements in shaft kilns, and it relates more particularly to a rotatable bottom in shaft kilns for calcining cement, lime, and similar substances.

It has already been proposed to use in lime kilns, gas producers, and kilns for treating non-sintering substances a worm-like or spiral member, or an organ having spirally disposed turns in stepped arrangement.

Such organs, which are preferably provided with large lateral crushing faces, are well adapted to handle relatively soft material, but they are not suitable for handling non-homogeneous sintering substances. In the latter case it is most difficult to obtain a uniform operation, and a consequent even sinking of the material under treatment.

The object of the present invention is to provide a rotary kiln bottom, which assures an uninterrupted uniform disposal of the sintering material, no matter what the direction of rotation of the bottom.

The rotatable kiln sole, according to our invention, is characterized by two sets of knife-like cutting edges, of which the one set operates in the one direction of rotation and the other set in the opposite direction of rotation of the bottom, and which cutting edges are arranged on a working (delivery) surface or facing extending from the crusher-head surmounting the bottom to the latter's outer rim of largest circumference, and which extend crosswise of a spirally extending delivery or discharge edge forming the boundary of the working surface. The outer discharge edge, as well as the working surface, ascend from the bottom rim toward the central crusher-head.

The cutting edges are preferably raised somewhat relative to the respectively adjoining step of the working surface, and

there are further provided, for enhancing the action of the cutting edges, slot-like recesses or interstices between the individual steps. The delivery edge as well as the working surface can be extended clear to the apex of the crusher-head, and the latter may be provided with knife edges and eccentrically disposed attacking edges.

Our invention will best be understood, when described in connection with the accompanying drawings, in which—

Figure 1 represents a vertical section through the lower part of a running shaft kiln, provided with a rotary bottom of our invention;

Fig. 2 shows a section on line A—B of Fig. 1;

Figs. 3 and 4 represent respectively a side elevation and a plan view of a somewhat modified construction of rotary bottom, and

Figs. 5 and 6 show respectively similar view of still another modification.

In the lower discharge end of the shaft kiln 1 is arranged the bottom 2 substantially cone-shaped, which is supported by the shaft 3 and is surmounted by the crusher-head 4 having a greater base angle than the body 2 and, which serves to break-up the clinker and is formed somewhat like a boring-head. The shaft 3 is operated in the one or the other rotary direction by a driving gear 5, located below the kiln proper.

The bottom 2, which is provided with the peripherally disposed extensions 6, has a discharge edge 7, spirally extending from the rim of the bottom toward its center and ascending from the bottom rim to the crusher-head 4. The bottom or body 2 is provided with substantially flat wedge-shaped sector like projections, each having an edge 7 and an edge 8 or 9, so that the projections are arranged step-wise in both a radial and a vertical direction in a single spiral. This edge 7 forms the outer boundary line of a working surface or facing 15, and it co-operates with two sets of knife-like cutting edges 8 and 9 respectively, which extend crosswise of the edge 7. The edges 8, of which there are more than of the edges 9, act on the clinker when the bottom rotates in the direction of the arrow —C—, while the edge or edges 9 operate on rotation in the sense of arrow —D— (Fig. 2).

Upon the bottom being rotated by the gear 5 in the direction of the arrow —D—, that is to say in the direction opposite to that

of the pitch of the edge 7, this latter will cause the broken-off clinker to be shoved outwardly toward the periphery of the bottom 2, from where it then drops onto a downwardly directed annulus 10 of the kiln, and is finally dumped down the chute 11 into a suitable conveyer, not specifically shown here.

In this manner, on the bottom rotating in the indicated sense, we obtain an uninterrupted and uniform breaking-up and discharging of the sintering kiln contents. At the same time the cutting edges 8 will be sharpened on the clinker mass, while the edge 9 effects the slicing of the clinker. On the bottom revolving in the sense of the arrow —C—, the edges 8 will cut the clinker, and the edge 9 will be whetted.

In order to enhance the action of the edges 8, there is provided ahead of each edge an interstice 12.

In the constructional modification according to Figs. 3 and 4, the edge 7 as well as the facing 15, extend clear to the top of the crusher-head, and there are provided at the top knife-edges 13 and eccentric attacking edges 14.

In the modification shown in Figs. 5 and 6, the interstices or slots 12' are more deeply recessed and form grooves, whereby the operative surface is still further enlarged.

What we claim is:

1. In a shaft kiln, a rotary support for material consisting of a substantially cone-shaped head provided with substantially flat topped projections arranged in the form of a single spiral, said projections having cutting edges adapted to cut when said head is rotated in either direction.

2. In a shaft kiln, a rotary support for material, consisting of a substantially cone-shaped head provided with substantially flat-topped projections and arranged stepwise in both a vertical and peripheral direction in a single spiral, said steps having cutting edges increasing in length with the increase in length of the radii of the spiral.

3. In a shaft kiln a rotary support for material, consisting of a substantially cone-shaped head provided with substantially flat-topped projections and arranged stepwise in both a vertical and a peripheral direction in a single spiral, each step having both a substantially radial and a substantially vertical cutting edge.

4. In a shaft kiln a rotary support for material, consisting of a substantially cone-shaped head provided with substantially flat-

topped projections and arranged stepwise in both a vertical and a peripheral direction 60 in a single spiral, each step having both a substantially radial and a substantially vertical cutting edge, some of said cutting edges adapted to cut when said head is rotated in one direction and the other cutting edges 65 adapted to cut when said head is rotated in the other direction.

5. In a kiln, a rotary support for material, consisting of a substantially cone-shaped head provided with substantially flat-topped projections spaced apart and arranged in the form of a single spiral, said projections having cutting edges adapted to cut when said head is rotated in either direction, and the apex of said head being provided with projections elongated lengthwise 75 of the cone axis.

6. In a kiln, a rotary support for material, consisting of a substantially cone-shaped head, surmounted by a crusher head 80 and provided with substantially flat-topped projections spaced apart and arranged in the form of a single spiral, said projections having cutting edges adapted to cut when said head is rotated in either direction, and the apex of said head being provided with projections elongated lengthwise 85 of the cone axis, and a downwardly inclined discharge member below said head.

7. In a kiln, a rotary support for material, consisting of a substantially cone-shaped head provided with wedge-shaped spiral sector-like projections spaced apart and arranged in the form of a single spiral, 90 said projections having cutting edges adapted to cut when said head is rotated in either direction, and the apex of said head being provided with projections elongated lengthwise 95 of the cone axis.

8. In a shaft kiln, a rotary support for 100 material, consisting of a substantially cone-shaped head provided with substantially flat-topped projections spaced apart and arranged in the form of a single spiral, said projections having cutting edges radially 105 offset from one another and adapted to cut when said head is rotated in either direction, and the apex of said head having a greater base angle than the body thereof and provided with projections elongated 110 lengthwise of the cone axis.

In testimony that we claim the foregoing as our invention, we have signed our names.

ARNOLD STEIGER.
WILHELM STEIGER.
